UNITED STATES PATENT OFFICE.

LEONARD B. CORNELL, OF SPOKANE, WASHINGTON.

PIN-FASTENING.

1,405,761.

Specification of Letters Patent. Patented Feb. 7, 1922.

Application filed September 13, 1921. Serial No. 500,839.

To all whom it may concern:

Be it known that I, LEONARD B. CORNELL, a citizen of the United States, residing at Spokane, in Spokane county, and State of Washington, have invented certain new and useful Improvements in Pin-Fastenings, of which the following is a specification.

My present invention relates to improvements in pin fastenings for use in connection with buttons, badges, eyeglass holders, and other comparatively light articles of this nature by means of which they may be temporarily but securely attached to the clothing or other fabric. The primary object of the invention is the provision of a pin fastening for this purpose having two aligned points for penetration of the supporting material, which may be constructed or manufactured at comparatively slight expense, which is simple in construction and facile in manipulation for fastening or unfastening, and which is capable of securely holding the article to which it is attached. With these and other objects in view the invention consists in certain novel combinations and arrangements with the article to be supported of a single or one-piece pin fastening having both a rigid fastening and a flexible or resilient fastening member which co-act in such manner as will be described. In the accompanying drawings I have illustrated one complete example of the physical embodiment of my invention wherein the parts are combined and arranged according to the best mode I have thus far devised for the practical application of the principles of my invention, but it will be understood that changes and alterations may be made within the scope of my appended claim without departing from the spirit of my invention.

Figure 1 is a plan view of a button or badge, showing the fastening device of my invention attached at the back or rear side thereof.

Fig. 2 is an edge view of the device of Fig. 1.

Fig. 3 is a view of the pin fastening detached from the article to be supported.

Fig. 4 is a side or edge view of the device showing it attached to a piece of fabric, which may be a portion of clothing, drapery, or the like.

In the preferred form of the invention as illustrated in the drawings while I have shown the article 1 to be supported, as a

badge or button, it will readily be understood that this article may be of other suitable shape, and designed for numerous other purposes, and is therefore to be understood as merely illustrating one use of the pin fastening device.

The fastening device as shown is of a single piece of metal in the form of wire, fashioned to desired shape, and possessing resiliency sufficient for the purpose of the invention. The portion 2 of the fastening is a straight, rigid member pointed at 3, which may if desired project slightly beyond the periphery of the button or badge 1. This straight portion of the fastening device is rigidly secured to the rear of the button or badge by means of the metal plate or cleat 4 which may be soldered to the pin and to the rear face of the badge, or otherwise secured to these members to afford a rigid and secure anchorage for the fastening device. The metal of the pin is resilient and the pointed pin 2 may thus be bent sufficiently to permit the entrance of the point 3 into the fabric and a portion of the fabric may pass between the pin 2 and the rear face of the button, as seen in Fig. 4.

At the opposite side of the attaching plate 4, the pin 2 is fashioned with a lateral bend 5 and terminates in a second pointed portion or member 6, which is aligned with the pointed pin portion 2, the whole member extending axially or diametrically across the circular button with the two pin or pointed portions in alignment. From the attaching plate 4 to the pointed end of the pin-portion 6 the fastening device is free of the badge, but lies snugly thereagainst, and because of the resiliency of the metal or material of the device the pin may be flexed by closing the bend 5, and slightly bent from the button to permit insertion of the pointed part 6 into the fabric. At 7 a head is shown on the pin 6 which prevents excessive penetration of the pin 6 into the fabric to which the device is to be attached, as illustrated in Fig. 4.

The utility of the fastening device will be apparent, and the modus operandi of attachment is quite simple. The pin portion 6 is first inserted into the fabric until the head 7 encounters the fabric and forms an abutment and pressure is continued on the button until the open bend 5 is partially or completely closed. This movement will draw the point 3 beyond its normal position with relation to the fabric, and when pressure is

released on the button, the point 3 is guided to penetrate the fabric, and the released pressure permits the resilient bend 5 to expand. By the expansion of the bend 5 and 5 the separation of its two arms, the point 3, together with the button, is bodily moved and the point is caused to penetrate the fabric, as in Fig. 4. Under these conditions, the expanded, resilient bend 5 exerts its pressure 10 on both the alined pin portions 2 and 6 retaining these members in proper position, the fabric is stretched taut back of the button, and the button is held securely in proper position.

15 To unfasten the button, pressure is applied thereto to close the bend or bow 5 and withdraw the point 3 from the fabric, then the pin 6 may be withdrawn from the fabric and the button released. In order that the pins 20 may not protrude through the clothing of

the wearer, when applying the fastening devices, it may be well to slightly deflect the points inwardly, toward the person of the wearer, thus preventing exposure through the fabric and consequent danger of catching on the fingers, but of course the pin points will not be deflected sufficiently to penetrate the clothing of the wearer. 25

Having thus fully described my invention, what I claim as new and desire to secure by 30 Letters Patent is—

The combination with a button of a pin fastening rigidly joined thereto and comprising a straight pin portion at one side of the joint and an alined pin portion at the 35 other side of said joint, a resilient bow formed in the second pin portion, and a head on said pin portion beyond the bow.

In testimony whereof I affix my signature.
LEONARD B. CORNELL.
